(57) **CLAIM**

The ornamental design for a mobile phone, as shown and described.

DESCRIPTION

FIG. 1 is a back perspective view of a mobile phone, showing my new design;

FIG. 2 is a front plan view thereof;

FIG. 3 is a back plan view thereof;

FIG. 4 is a left elevation view thereof;

FIG. 5 is a right elevation view thereof;

FIG. 6 is a top elevation view thereof; and,

FIG. 7 is a bottom elevation view thereof.

The broken lines in the drawings are for the purpose of illustrating portions of the mobile phone that form no part of the claimed design.

1 Claim, 7 Drawing Sheets
